SAFETY ASH TRAY

Leon W. White, Pittsfield, Mass.

Application March 28, 1945, Serial No. 585,341

1 Claim. (Cl. 131—235)

1

This invention relates to smoker's appliances and has for an object to provide an ash tray which will eliminate fire hazard caused by cigarettes when the tray is used.

Another object of the invention is to provide an ash tray having an inclined edge wall upon which a cigarette cannot be balanced.

A further object of this invention is to provide an ash tray having a series of snuffing compartments.

A still further object of my invention is to provide an ash tray so formed that, neither a cigarette nor its ash can fall from the tray under any condition.

Other features and advantages will become more readily apparent from the following description and the accompanying illustrative drawings in which:

Figure 1 is a top plan view of my improved ash tray,

Figure 2 is a vertical sectional view thereof, and

Figure 3 is a diagrammatic section of the invention.

In the accompanying drawings as above enumerated and in the following specification, like characters of reference indicate like parts throughout and in which 10, illustrates my improved ash tray which consists of a cylindrical container 11, divided by a series of walls or partitions 12, into cigarette snuffing compartments 13. Each of said walls 12, incline upwardly to an annular flange 14, which flange is fluted throughout its length, and the ridges 15 and 16, dividing said flutings inclining to said walls 12, as indicated at 17, in Figure 2 of the drawings.

The walls 12 include outer vertical edges 18 that engage the inner periphery of the cylindrical container or cylindrical wall 11.

The member 11, is provided with an inner cylindrical member or wall 18, at which the inner vertical edges 18 of the walls 12, terminate. The upper inner ends 19, of the walls 12, terminate at the upper surface 20, of the member 18. An annular flange 21, is provided on said surface 20, against which the burning end 22, of a cigarette 23, may rest, said flange forming a stop to limit the down movement of the cigarette. Projecting from the center of said member 20, is a U-shaped member 24, the arms 25 and 26, of which

are turned away from one another and formed arcuately as indicated at 26' and 27, to provide holders into which cigarettes may be laid.

The distance *d* between the inner vertical edges of adjacent partitions is considerably less than the diameter of a cigarette to permit the mashing of a cigarette as the same is moved between an adjacent pair of partitions 12 and toward the inner cylindrical wall 18.

From the foregoing, it will be seen that I have provided an ash tray for supporting lighted cigarettes but so arranged that no such cigarette can be laid thereon in any manner whereby if left on the tray it can possibly burn out and fall over the edge of the tray but if left lighted the cigarette must fall from the support 20, at said lighted end, into one of the snuffing compartments 13, the bottom portion 28, of which is practically excluded from air and the cigarette will soon die out as far as its lighted end is concerned. A smoker still using the cigarette may seat it against the edge 14, of the tray with its lighted end 22, upon said support 21, but if he has finished the smoking thereof, he can seat it upright into one of the compartments 13, as indicated at 29, of Figure 3.

It is thought that persons skilled in the art to which the invention relates will be able to obtain a clear understanding of the invention after considering the description in connection with the drawings. Therefore, a more lengthy description is regarded as unnecessary.

Minor changes in shape, size and rearrangement of details and parts such as come within the purview of the invention claimed may be resorted to, in actual practice, if desired.

Having now described my invention that which I claim as new and desire to procure by Letters Patent is:

An ash tray comprising inner and outer concentric cylindrical walls, and a plurality of circumferentially spaced radially disposed partitions joining the inner and outer walls, said partitions being of a length substantially equal to the diameter of said inner wall, each of said partitions including an outer vertical edge and an inner vertical edge, and the distance between the inner vertical edges of adjacent partitions being considerably less than the diameter of a cigarette to permit the mashing of a cigarette as

the same is moved between an adjacent pair of partitions and toward the inner wall.

LEON W. WHITE.
